UNITED STATES PATENT OFFICE.

MINNIE CASMIER, OF SOUTH BEND, INDIANA, ASSIGNOR TO STEPHENSON UNDERWEAR MILLS, OF SOUTH BEND, INDIANA, A CORPORATION OF INDIANA.

UNION GARMENT.

1,161,842.

Specification of Letters Patent. Patented Nov. 30, 1915.

Application filed April 4, 1913. Serial No. 758,784.

To all whom it may concern:

Be it known that I, MINNIE CASMIER, a citizen of the United States, residing at South Bend, in the county of St. Joseph 5 and State of Indiana, have invented certain new and useful Improvements in Union Garments, of which the following is a specification.

The invention relates generally to an improvement in union garments, being more particularly directed to a union garment in which the improved construction provides a permanently closed crotch, while at the same time providing sufficient material for proper 15 fitting without the use of relatively large and unsightly flaps or drop sections.

The main object of the present invention is the provision of a gusset of peculiar formation and construction, which when combined with a union garment appropriately cut for the reception of the gusset assures a desirable and necessary feature of a union garment, while at the same time providing 20 permanently closed crotch portion.

25 The invention in its preferred form of details will be described in the following specification, reference being had particularly to the accompanying drawings, in which:—

Figure 1 is a front elevation of the improved union garment. Fig. 2 is a rear elevation of the same. Fig. 3 is an enlarged broken front elevation with the leg portions turned up to show the leg and crotch portions of the gusset. Fig. 4 is a broken rear elevation showing the closing flap in-open 35 position. Fig. 5 is a view of the gusset. Fig. 6 is a view of the flap.

In the present invention the union garment for which the improvements are particularly designed, is preferably made of the usual tubular webbing which for the purpose of the present invention is divided on a median line extending from the neck 40 downwardly to the crotch portion and upwardly along the back terminating at a point slightly above the waist line. The line of division 2 thus provided communicates with similar lines of division 3 extending from the crotch down the leg portions for a short distance, so that in the initial 45 step the garment is divided from the neck, through the crotch and up the back, the leg portions from the crotch outwardly being also divided on their under sides for a 50 short distance.

In conjunction with the garment as thus formed I use a gusset which is shown more particularly in Fig. 5. This gusset is integrally constructed of a single piece of appropriate material cut to form a main portion 4, having upwardly converging side edges 5. The main portion is provided with depending spaced leg portions 6, which normally incline inwardly or toward each other, the juncture of the outer edges of the main 60 portion and leg portions being notched at 7 to provide for the proper application of the gusset without forming a fold. The lower edge of the main portion intermediate the leg portions presents downwardly converging marginal edges 8, so that between the leg portions the main portion terminates in approximately triangular shaped crotch portion 9. The main portion of the gusset from the relatively upper edge thereof to the 70 point above the crotch portion is longitudinally slitted or divided upon a median line as at 10.

The gusset is secured in place by uniting the outer edges 5 of the main portion between and to the respective edges of the line of division 2 of the back, the leg portions 6 being similarly secured between and to the respective edges of the lines of division 3 of the legs. This provides the desired enlargement of the garment about the posterior and upper parts of the legs, it being understood that that portion of the gusset below the lower terminal of the line of division 10 of the slit and the marginal edges 8 of the 80 main portion of the gusset form a permanently closed crotch portion for the garment.

To close the line of division 10 of the gusset I provide a flap shown more particularly in Fig. 6, comprising an integral section of material 11 having a straight marginal edge 12 which is secured directly to the gusset on one side of the line of division 10 thereof, the flap having an opposing marginal edge 13 on opposite angularly related lines, the width of the flap being sufficient to overlap throughout at least a portion of its length the line of juncture between the gusset and garment proper throughout one edge of the main portion 4 of the gusset. The flap in the adjacent free edge is formed with a button hole 14 to cooperate with a button 15 secured on the garment, whereby with the flap fastening in place the opening or line of 110

division in the gusset, which as will be understood forms a necessary rear opening in the garment, is covered, and the person thus protected.

- 5 In the particular type of union suits to which this improvement relates, it has been difficult in the past to provide a sufficient posterior opening and at the same time a permanently closed crotch without the employment of relatively large and unsightly as well as uncomfortable flaps or drop sections, and the salient feature of the present invention, therefore, resides in a means by which this difficulty is overcome, namely, in
- 10 the provision of a single gusset, itself dividing to form the posterior opening, while at the same time being formed to provide a permanently closed crotch.
- 15 What is claimed is:

- 20 1. A union garment divided through the crotch portion and up the back to a point approximating the waist line, the legs of the garment being divided from the crotch portion toward their free ends, a single piece
- 25 gusset including an unbroken crotch portion, leg sections and a main section, the marginal edges of said gusset being secured to the respective edges of the division in the garment, said gusset being divided longitudinally and centrally from its upper edge to a point above the crotch portion, and a flap secured throughout one marginal edge and the gusset adjacent the line of division therein, and means for securing the flap to the garment to close the line of division in the gusset.
- 30 2. A union garment divided through the

crotch portion and up the back to a point approximating the waist line, the legs of the garment being divided from the crotch portion toward their free ends, in combination with a single piece gusset including a main portion having an upper end of appreciable width and converging side edges, the gusset including leg sections of comparatively narrow width disposed in line with and at an angle to the side edges of the main section, said main section being longitudinally and centrally divided from its upper edge to a point approximately in line with the upper ends of the leg sections, the marginal edges of the gusset being secured throughout its full marginal edge to the respective edges of the division in the garment.

3. A single piece gusset for union garments including a body having side edges of upwardly converging formation and an upper edge of appreciable length, the body portion having integral extensions projecting from the lower edge thereof, the side edges of said extensions meeting the side edges of the body on angular lines, the lower edge of the body intermediate the adjacent edges of the extensions being of V-shape, said body being divided longitudinally from a point immediately above the extensions to and through the upper edge.

In testimony whereof I affix my signature in presence of two witnesses.

MINNIE CASMIER.
